UNITED STATES PATENT OFFICE.

JAMES E. RIDGWAY, OF ATCHISON, KANSAS.

SEWING-MACHINE NEEDLE.

No. 884,857.

Specification of Letters Patent. Patented April 14, 1908.

Application filed August 1, 1907. Serial No. 386,638.

To all whom it may concern:

Be it known that I, JAMES E. RIDGWAY, a citizen of the United States, residing at Atchison, in the county of Atchison and State of Kansas, have invented a new and useful Sewing-Machine Needle, of which the following is a specification.

This invention has reference to improvements in sewing machine needles, and is designed to produce an easily threaded needle having a guideway for the thread, whereby the latter is directed through the cloth being sewed.

The invention consists essentially in a needle having a longitudinal slit leading from the lower end of the eye to a point near the shank enlargement designed to enter a clamp on the sewing machine arm, at which point the slit is enlarged and has an angle extension so shaped that the exterior of the needle has no projecting parts while at the same time that portion of the needle divided from the main body by the thread-receiving slit is prevented from moving beyond the plane of the surface of the needle. There is also provided in the line of the slit a longitudinal thread-receiving recess extending in the plane of the eye of the needle to a point about concentric with the end of the slit.

The eye of the needle is likewise improved by making the same circular in cross section, for certain purposes, with a diamond finish or cut on each side of the needle merging into the eye. Likewise, the slit is arranged to divide the needle stem through the greater portion of its length into two equal parts and only when approaching the eye does this slit leave the central plane of the needle, finally entering the eye near the lower side thereof, so that the thread, once lodged in the eye, can not during the act of sewing be accidentally diverted again into the slit.

The invention will be fully understood from the following detailed description, taken in connection with the accompanying drawings forming part of this specification, in which,

Figure 1 is an elevation, with parts in section, of a needle constructed in accordance with the present invention, but with the proportions of the parts greatly exaggerated; Fig. 2 is a similar view of the lower or point end of the needle, viewed from the side opposite that shown in Fig. 1; Fig. 3 is a cross section on the line $w-w$ of Fig. 1; Fig. 4 is a cross section of the line $x-x$ of Fig. 1; Fig. 5 is a

cross section on the line $y-y$ of Fig. 1; and Fig. 6 is a cross section on the line $z-z$ of Fig. 1.

Referring to the drawings, there is shown a sewing machine needle composed of a body portion or stem 1, a point 2, and a shank 3, which latter is for the purpose of securing the needle in the sewing machine arm and may be suitably shaped therefor. The general contour of the needle is that of an ordinary sewing machine needle but in the drawings the eye 4 of the needle is shown as circular in cross section and on each side there is a dished or recessed portion 5 of general diamond shape and with all the edges rounded and constituting a diamond finish or cut. This is the form to be employed when the needle is used for sewing silk and harsh goods, while an oblong diamond cut eye is preferable for leather, heavy drilling goods, and other heavy work.

Extending centrally along one side of the needle is a longitudinal groove 6 merging at the point end of the needle into the corresponding diamond cut 5 and extending beyond the other end nearly to the shank 3. Other than this longitudinal groove or depression the stem 1 is cylindrical between the eye and the shank.

Extending diametrically through the needle body from the base of the groove 6 to the other side of the needle is a slit 7 terminating at one end in an enlargement 8 near the shank 3 and at the other end diverted from the longitudinal diametric plane of the needle toward one side thereof, as indicated at 9, and this slit ultimately enters the eye 4 near the lower edge thereof. Consequently, there is an overhang or lip 10 on one side of the eye and out of the path of the thread when under the strain of sewing, so that there is no danger of the thread again entering the slit after having been once lodged in the eye. Entering the enlarged portion 8 of the slit is another angle slit 11, directed from the exterior of the needle stem diagonally upward until it opens into the enlargement 8. The needle stem is, therefore, throughout the greater portion of its length, divided into two equal portions, one of which is integral with the shank 3 and point 2, and the other portion 12 is connected to the first-named portion only at a point about coincident with the eye. Opposite the enlargement 8 the portion 12 is reduced in diameter, as shown at 13, so as to be elastic, thus permitting this portion of the

section 12 to yield inwardly when the thread is brought to bear against the exterior thereof and thus so opening the slit 11 that the thread will find passageway into the enlargement 8. As soon as the section 13 is relieved from the pressure due to the effort to force the thread through the passage 11 it will spring back and its exterior surface will then be coincident with the exterior surface of the 10 upper portion of the needle adjacent thereto. When the thread is drawn down toward the end of the needle through the slit 7 the portion 12 of the needle will yield to permit the passage of the thread until finally such 15 thread finds lodgment in the eye 4.

Now, when the needle is in operation that portion of the thread which is coming from the supply lies along the recessed or grooved side of the needle. Therefore, the thread is 20 housed in this groove out of the path of the cloth strands, and, being in the central longitudinal plane of the needle stem and in line with the eye, it cannot cause a deflection of the needle point from its true path since the 25 upper end of the portion 13 of the part 12 will engage the adjacent portion 14 of the main part of the needle stem.

I claim:—

1. A sewing machine needle comprising a 30 stem having a longitudinal groove formed in one side and merging into the eye of the needle, and a slit coincident with the groove to the greater portion of its length and extending diametrically through the needle stem 35 throughout the coincidence of the slit with

the groove, said slit diverging from its diametric course near the eye end of the stem and entering the eye below the center of the latter and also having its upper end formed with an enlargement located at one side only 40 of the diametric plane of the slit and provided with a diagonal passageway leading to the exterior of the stem on the same side of the slit as is the divergent end entering the eye of the needle.

2. A sewing machine needle comprising a stem having at the point end a circular eye with diamond cuts or recesses on each side, a longitudinal groove formed on one side and merging into the corresponding diamond cut, 50 and a slit coincident with the groove through the greater portion of its length and extending diametrically through the needle stem throughout the coincidence of the slit with the groove, said slit diverging from its diametric course near the eye end of the stem and entering the eye below its center, and also having its upper end formed with an enlargement located at one side of the diametric plane of the slit and provided with a diagonal passageway leading to the exterior of the stem.

In testimony that I claim the foregoing as my own, I have hereto affixed my signature in the presence of two witnesses.

JAMES E. RIDGWAY.
